(57) **CLAIM**

The ornamental design for an adjustable multipurpose anti-unhooking hook, as shown and described.

DESCRIPTION

FIG. 1 is a perspective view of an adjustable multipurpose anti-unhooking hook showing my new design;

FIG. 2 is another perspective view thereof;

FIG. 3 is another perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a front view thereof, shown in a first in-use condition;

FIG. 11 is a front view thereof, shown in a second in-use condition; and,

FIG. 12 is a front view thereof, shown in a third in-use condition.

1 Claim, 12 Drawing Sheets
